Hiram A. Sturges
Attorney

UNITED STATES PATENT OFFICE.

HENRY C. MILLER, OF OMAHA, NEBRASKA, ASSIGNOR TO JULIA A. MILLER AND LAURA B. COPE, BOTH OF OMAHA, NEBRASKA.

DRAWER-STOP.

1,295,186.

Specification of Letters Patent. Patented Feb. 25, 1919.

Application filed December 9, 1918. Serial No. 265,861.

To all whom it may concern:

Be it known that I, HENRY C. MILLER, a citizen of the United States, residing at Omaha, in the county of Douglas and State 5 of Nebraska, have invented certain new and useful Improvements in Drawer-Stops, of which the following is a specification.

This invention relates to an improvement in stops for furniture drawers, and has for 10 its object to provide such a construction that the longitudinal movements of a drawer will be limited, and particularly that its removal from accidental causes or otherwise, when drawn outwardly, will normally be 15 prevented, but to have such an arrangement of parts that removal will be permitted and that while being removed from a desk or other support, it may be maintained in a horizontal position. Another object is to 20 provide a stop for drawers which will consist of few and simple parts so that manufacture will be practical and economical.

With the above objects in view, the invention presents a novel construction, combination and arrangement of parts as described herein and claimed, and as illustrated in the accompanying drawing, it being understood that changes in form, size, proportion and minor details may be made 30 within the scope of the invention as claimed.

In the drawing, Figure 1 is a plan view of a drawer and its housing, parts being in section. Fig. 2 is a side view of a drawer. Fig. 3 shows a side view of the drawer 35 when drawn outwardly from a desk or other article of furniture.

Referring now to the drawing for a more particular description, the invention is illustrated in connection with a desk 4 or similar 40 article having upright partitions 5 between which the drawer 6 may normally have horizontal, slidable movements.

For purposes of the invention one of the side walls *a* of the drawer is provided with 45 a pair of apertures 7 and 8, the aperture 7 preferably being disposed adjacent to the inner end *b* of the drawer, and the aperture 8 being disposed intermediate the aperture 7 and the front end *c* of the drawer.

50 Numeral 9 indicates a flat spring disposed in line with apertures 7 and 8 and secured upon the inner side of a wall *a* of the drawer, one of its ends being secured to said wall by screws or equivalent keepers 9', said 55 spring being provided intermediate its ends

with a projection 10 adapted to engage in the aperture 8 and having a terminal hook or 60 detent 11 disposed within and, by force of the spring, projecting outwardly of the aperture 7.

Numeral 12 indicates a rectilinear groove or slot formed in the inner face of one of the partitions 5, one of its ends terminating at *e*, adjacent to the front end of said partition, and it will be understood that the 65 drawer may have an outward slidable movement until the detent 11 engages the stop *e* which prevents a further movement, the parts then being substantially in the position shown in Fig. 3. And when disposed 70 in the last named position, the drawer may be removed from the desk, if desired; and for this purpose the spring may be moved inwardly by manually pressing the projection 10 inwardly of the aperture 8 which 75 causes the detent 11 to be withdrawn from the slot or groove 12.

One of the advantages to be derived by 80 use of the invention is the feature which permits the drawer to be maintained in a horizontal position while it has a slidable, outward movement, this being a matter of importance when it is required to remove the drawer from the desk, since its contents will not become displaced.

By referring to Fig. 1 it will be seen that 85 the walls of the aperture 8 are formed outwardly divergent so that access may be convenient for moving the projection 10 inwardly against the force of the spring 9, 90 and in operation, for removing the drawer from the desk, as is often required, the inward pressure against said projection, as above mentioned, will cause the detent to move out of the slot, and a removal of the 95 drawer may be effected, as is obvious while the drawer is maintained in a horizontal position.

It will be noted that the inner terminal *a* of the slot 12 operates to limit the inward, 100 slidable movement of the drawer, so that when the latter is closed its front end will be disposed in line with the front part of the desk, as shown in Fig. 1.

What I claim as new and desire to secure 105 by Letters Patent is,—

1. In a stop for the drawer of a desk or similar article of furniture, the latter being provided with upright walls providing a housing for the drawer and having a groove 110

formed in one of its walls to terminate adjacent to one of its ends, a drawer provided with a pair of apertures in one of its sides and disposed in said housing for normal 5 slide movements longitudinally therein, a flat spring provided with a projection and a detent, said spring being secured to the side and disposed with its projection engaging in one of said apertures with its detent engaging in the other aperture of said pair and extending outwardly of the drawer to normally engage in said groove for limiting the slide movement of the drawer.

2. In a mounting for a desk drawer, said 15 desk providing a housing for the drawer and being provided with a stop, a drawer having apertures formed in one of its sides and normally adapted to be reciprocated longitudinally in said housing, a spring mounted 20 upon the inner side and having projections engaging in said apertures, one of said projections extending outwardly of the side of the drawer for engaging the stop of said desk during one of the longitudinal movements of the drawer.

3. In a drawer stop, the combination with a support provided with a horizontal groove having a terminal, a drawer having one of its sides provided with an aperture and a second aperture and normally adapted to have longitudinal reciprocation, a spring provided with a detent and disposed in line with said apertures, said spring being secured to a side of the drawer with its detent traversing the first named aperture and projecting outwardly of the side of the drawer to be disposed in said horizontal groove to normally limit a longitudinal movement of the drawer in one direction, said spring hav-

ing a projection disposed in the second aperture of the drawer to be moved inwardly of said drawer for disengaging the detent from said groove.

4. In a mounting for a drawer, a stationary housing provided with a stop, a drawer 45 adapted normally to be reciprocated longitudinally in said housing, said drawer having one of its sides provided with an aperture and a second aperture, a spring mounted on the drawer and having a detent traversing the first named aperture for engaging said stop during one of the longitudinal movements of said drawer, said spring also having a projection disposed in the second aperture of the drawer to be moved inwardly of the latter for disengaging said detent from said stop.

5. In a mounting for a drawer, a stationary housing provided with a stop and a second stop, a drawer adapted normally to be reciprocated longitudinally in said housing, one of the sides of said drawer being provided with an aperture having outwardly divergent walls, a spring mounted upon and having a detent traversing and projecting outwardly of one of the sides of the drawer to normally be disposed in the plane of said stops, said spring having a projection disposed in the aperture of the side of the drawer to be moved inwardly of the latter for moving said detent outwardly of the plane of said stops.

In testimony whereof, I have affixed my signature in presence of two witnesses.

HENRY C. MILLER.
